(57) **CLAIM**

I claim the ornamental design for a height adjustable workstation, as shown and described.

DESCRIPTION

FIG. 1 is a top perspective view for a height adjustable workstation in an extended configuration, showing my new design;

FIG. 2 is a bottom perspective view of the height adjustable workstation of FIG. 1;

FIG. 3 is a front elevation view of the height adjustable workstation of FIG. 1;

FIG. 4 is a rear elevation view of the height adjustable workstation of FIG. 1;

FIG. 5 is a right side elevation view of the height adjustable workstation of FIG. 1;

FIG. 6 is a left side elevation view of the height adjustable workstation of FIG. 1;

FIG. 7 is a top plan view of the height adjustable workstation of FIG. 1;

FIG. 8 is a bottom plan view of the height adjustable workstation of FIG. 1;

FIG. 9 is a top perspective view for the height adjustable workstation in a collapsed configuration;

FIG. 10 is a bottom perspective view of the height adjustable workstation of FIG. 9;

FIG. 11 is a front elevation view of the height adjustable workstation of FIG. 9;

FIG. 12 is a rear elevation view of the height adjustable workstation of FIG. 9;

FIG. 13 is a right side elevation view of the height adjustable workstation of FIG. 9;

FIG. 14 is a left side elevation view of the height adjustable workstation of FIG. 9;

FIG. 15 is a top plan view of the height adjustable workstation of FIG. 9; and,

FIG. 16 is a bottom plan view of the height adjustable workstation of FIG. 9.
